UNITED STATES PATENT OFFICE.

LEWIS F. STOUT, OF LOCKPORT, NEW YORK.

JAR-CLOSURE.

1,151,303.

Specification of Letters Patent. Patented Aug. 24, 1915.

Application filed September 5, 1913. Serial No. 788,298.

To all whom it may concern:

Be it known that I, LEWIS F. STOUT, a citizen of the United States, residing at Lockport, in the county of Niagara, State of New York, have invented certain new and useful Improvements in Jar-Closures, of which the following is a description, reference being had to the accompanying drawing and to the figures of reference marked thereon.

10 This invention relates to new and useful improvements in jar closures.

Much difficulty has been experienced in sealing fruit jars of the screw top type, such 15 as are known to the trade as the Mason fruit jars. This difficulty is occasioned by the fact that the mouths of the jars have, from time to time, been formed of different sizes and consequently the sealing rings used 20 at one time are not of a proper size for a later sized jar. Furthermore, much trouble is encountered by the user in obtaining the proper sized rings for the reasons above specified.

25 The principal object of my invention is, therefore, to provide a sealing means for this particular type of jar, by means of which jars of different sizes may be readily sealed.

30 Another object of the invention is to provide a sealing device which, after the jar has been sealed, may be removed from said jar for further use.

A still further object of the invention is 35 to provide a sealing means which will centrally bear upon the top or closure of the jar and thereby transmit a uniform pressure to said closure, thereby effectually sealing the jar.

40 In the accompanying drawings,—Figure 1 is a side elevation showing the application of my invention to the mouth of a jar; Fig. 2 is a top plan view thereof; Fig. 3 is an enlarged detail cross sectional view taken 45 centrally through the sealing device; Fig. 4 is a perspective view of the clamping member; and, Fig. 5 is a side elevation showing another form of the sealing device.

Like reference numerals designate corresponding parts in all figures of the drawings.

50 Referring to the drawings, I have illustrated a jar 5, which is of the Mason type and provided with an exteriorly threaded 55 mouth 6.

In one form of the sealing device, as is

illustrated in Figs. 1 to 4 inclusive, there is provided a clamping member 7, formed from flat spring metal and bent into U-shape. This member comprises a bridge 60 portion 8 and spaced clamping legs 9—9, the ends of said legs being curved inwardly to form thread-engaging feet 10—10. The inner edges of these feet are concaved, as at 11—11, to conform to the contour of the 65 threaded mouth 6. In order to impart sufficient strength to the bridge portion 8, said portion is provided with a plurality of spaced longitudinal ribs 12—12, said ribs being preferably formed by pressing the 70 metal of said portion.

Centrally formed in the bridge portion 8, between the ribs, is an elongated slot 13, this slot preferably terminating in spaced 75 relation to the legs 9. Formed in each leg 9, adjacent the bridge portion 8, is a centrally disposed opening 14.

Associated with the jar 5 is a top or closure 15, which is preferably formed of glass, although any other suitable material may be 80 employed.

In order to seal the jar 5 after the closure 15 has been placed thereon, the clamping member 7 is positioned to straddle the closure 15, and the spring legs 9—9 are caused, 85 through the feet 10, to frictionally engage the threads of the mouth 6 at diametrically opposite points. In order to force and retain the closure 15 upon the jar 5 through the medium of the clamping member 7, I 90 have provided a cam lever 16, which swings vertically in the slot 13 of said clamping member, and is formed at its lower end with laterally extending projections 17—17, constituting a cam. These projections of the 95 cam extend beyond the opposite sides of the slot 13 and are arranged to engage the under surface of the bridge portion 8, each engaging portion of the cam being rounded as at 18. Pivotedly connected to the lower 100 portion of this cam by means of a pin 19, or the like, is a shoe 20. This shoe is of U-shaped construction and the ears thereof are engaged by the pin 19. The body portion 21 of this shoe is disposed in spaced relation below the cam 17, and is adapted, when the lever is in its upright position, to engage the closure 15 of the jar.

In order to quickly elevate the shoe 20 from its engagement with the closure 15, 110 when the cam 17 has been disengaged from the bridge portion 8, I have provided a re-

silient means, which, in this instance, comprises an elongated flat spring 22. This spring is centrally bowed, as at 23, and this bowed portion is disposed intermediate the 5 cam 17 and the body portion 21 of said shoe. The ends of this spring are of sufficient length to extend through the openings 14 formed in the legs 9 and slightly therebeyond. By extending the ends of this 10 spring a short distance beyond the legs 9, said legs 9 may be sprung outwardly to engage jars of larger sizes without disconnecting said spring from said legs.

From the foregoing it will be observed 15 that when the parts are positioned upon a jar as above described, and the cam lever 16 is swung to a vertical position, the cam 17 will bear against the under surface of the clamping member 7 and tend to raise said 20 member. This movement will cause the feet 10 of said member to tightly engage the threads of the mouth 6 of the jar. At the same time the cam 17 will cause the foot 20 to be forced downwardly upon the closure 25 15 and against the tension of the spring 22. As soon as the lever 16 is swung to either side of the vertical line, the pivot 19 will be moved closer to the bridge portion 8 of the clamping member, carrying the shoe 20, 30 this upward movement of the shoe being assisted by the spring 22. The legs 9 can then be sprung outwardly and the sealing device thereby disengaged from the jar.

It will be observed in this connection that 35 by curving the feet 10 of the clamping member to conform to the curvature of the threads, a firm gripping means is thereby formed.

It will sometimes be found in practice that 40 after the device has been applied to the jar and the lever 16 actuated to seal said jar, that a sufficient pressure upon the closure 15 has not been made. This is due to the fact that the bridge portion 8 is disposed at a distance too far above the closure 45 15. When this is the case, the operator can readily rotate the clamping member upon the threads in the proper direction and thereby cause the bridge portion 8 to be 50 disposed closer to the closure 15 so that when the lever 16 is again actuated, the closure will be forced tightly upon the jar.

In the form illustrated in Fig. 5 of the drawings the clamping member 7 is not 55 formed with the opening 13 in the bridge portion 8, nor with the openings 14 in the legs 9. The bridge portion 8 in this form, however, is centrally formed with an upwardly extending interiorly threaded boss 24, and operating in this boss is a threaded stem 25 carrying at its upper end a hand wheel 26. Secured to the lower end of this stem by means of a ball and socket joint 27 60 is a foot piece 28. In practice, after the clamping member has been properly posi-

tioned to engage the threads of a jar, and the closure 15 positioned upon the mouth of said jar, the stem 25 is rotated by means of the hand wheel 26. As a result, the foot piece 28 will be caused to tightly bear upon 70 the closure 15 and at the same time cause the clamping member 7 to tightly engage the threads of the jar. By forming the ball and socket joint 27 between the stem 25 and foot piece 28, said foot piece will always be 75 properly positioned upon the closure 15, regardless of the angle assumed by the clamping member 7.

It will be observed that one of the legs 9 of the clamping member is longer than the 80 other leg to permit of the feet 10 being properly positioned to engage the thread at opposite sides of the jar.

While I have disclosed a jar having 85 threads formed at its mouth, it will, of course, be understood that any equivalent of the threads may be employed, such as, for instance, cam lugs.

From the foregoing it will be observed 90 that I have provided a clamping member 90 which includes spring legs carrying feet for engagement with the threads of jars of different sizes; and that a means is centrally carried by the clamping member, and cooperates with said member, to force the closure 95 tightly upon the jar.

It is obvious that minor changes in the details of construction and the arrangement of parts may be made without departing from the spirit of the invention, as set forth in 100 the appended claims.

Having thus described my invention, what I claim is:

1. In a sealing device for jars, the combination of an inverted U-shaped clamping 105 member formed from flat spring metal and comprising a bridge portion and spaced legs, the latter being formed with inwardly extending feet for engagement with the threads of a jar, said bridge portion being 110 formed with an elongated slot, a lever operating in said slot and formed with a cam at its lower end for engagement with said bridge portion, and a shoe pivotally connected to said cam for forcing the closure 115 downwardly upon the jar when the lever is moved to its locking position.

2. In a sealing device for jars, the combination of an inverted U-shaped clamping 120 member formed from flat spring metal and comprising a bridge portion and spaced legs, the latter being formed with inwardly extending feet for engagement with the threads of a jar, said bridge portion being 125 formed with an elongated slot, a lever operating in said slot and formed with a cam at its lower end for engagement with said bridge portion, a shoe pivotally connected to said cam for forcing the closure downwardly upon the jar when the lever is moved 130

to its locking position, and a spring disposed between the cam and the shoe and having its ends loosely mounted in the legs of said clamping element for elevating said shoe 5 from the closure when said lever is shifted to its releasing position.

3. In a sealing device for jars, the combination of an inverted U-shaped clamping member formed from flat spring metal, and 10 comprising a bridge portion and spaced legs, one leg being longer than the other to accommodate said clamping member to the threads of the jar, said legs having inwardly extending feet for engagement with said

threads, said bridge portion being formed 15 with an elongated slot, a lever operating in said slot and formed with a cam at its lower end for engagement with the bridge portion, and a shoe connected to said cam for forcing the closure downwardly upon the 20 jar when the lever is moved to its locking position.

In testimony whereof, I affix my signature, in the presence of two witnesses.

LEWIS F. STOUT.
